CALCULATING ATTACHMENT FOR TYPE-WRITERS

Charles H. Sampson, Rochester, N. Y.

Application April 5, 1932, Serial No. 603,365

8 Claims. (Cl. 235—60)

This invention comprises a calculating attachment for typewriting machines and has for one of its objects to provide an attachment embodying a calculating mechanism which is complete in itself and can be operated separately and jointly with the typewriting machine.

Another object of this invention is to so construct the attachment and its operating mechanism that its operation in combination with a typewriting machine is not dependent on a predetermined position of the carriage or any other part of the typewriting machine.

A further object of the invention is to provide a mechanism for the attachment which allows the amounts to be recorded and totalized in any desired position on any sheet, letter or bill placed in the typewriter.

Another object of the invention is to provide connecting means between the keys of the typewriting machine and the calculating attachment which are manually operated to have the typewriter keys operate the calculating mechanism and are automatically operated to disconnect the typewriter keys from the calculating mechanism after each set up or the clearing of the calculating mechanism.

These and other objects of the invention will become more readily apparent from the detailed description thereof which follows reference being had to the accompanying drawings in which

Figure 1 is a front elevation of a portion of a conventional form of a standard typewriter with the calculating attachment mounted thereon, some of the keys of the typewriter and the corresponding keys of the calculating attachment being omitted from the figure.

Figure 2 is a vertical sectional view of the calculating attachment, the section being taken on the line 2x—2x of Figure 1.

Figure 3 is a vertical sectional view of the calculating mechanism, the section being taken on the line 3x—3x of Figure 1.

Figure 4 is a rear elevation of the calculating mechanism.

Figure 5 is a vertical sectional view of the calculating mechanism partly broken away, the section being taken on the line 5x—5x of Figure 4.

Figure 6 is a horizontal sectional view of the calculating mechanism, the section being taken on the line 6x—6x of Figure 4.

Figure 7 is a vertical sectional view of the key operating mechanism of the calculating attachment and a diagrammatical sectional view of the typewriter to which it is attached.

Figure 8 is a front elevation of one of the digit rack bar assemblies.

Figure 9 is a longitudinal sectional view of the upper portion of the index pin carriage illustrating the friction springs which frictionally hold the index pins in place in the carriage and lock them in place therein.

In the several figures of the drawings like reference numerals indicate like parts.

The calculating attachment forming the subject matter of my present invention is adapted for use with any make of standard typewriter and when attached thereto transforms the typewriter into a calculating machine adapted for writing, listing, adding and multiplying without restriction as to how and where the writing and listing must be done on the sheet in the typewriter.

As illustrated in the several figures of the drawings, the mechanism of the calculating attachment is mounted on a vertical base plate 1 which extends across the front of the frame A of the typewriter where it supports the key operating mechanism and extends to one side of the typewriter frame A where it supports the calculating mechanism proper.

In Figure 7 the calculating attachment is illustrated attached to a portion of a standard typewriter in which A represents the frame thereof, B one of the type bars which is connected by means of a suitable link mechanism D to the key lever C of one of the numeral keys E. F represents the platen of the typewriter which is adapted to turn and travel endways over the frame and carries the paper sheet or sheets on which the typewritten matter, as well as the amounts from the calculating attachment, are recorded. The typewriter mechanism may be any one of the well known standard types of typewriters and the attachment of the calculating mechanism does not in any way affect the operation of the typewriter.

As above pointed out, the mechanism of the calculating attachment is entirely supported on the vertical base plate 1 which, as illustrated in Figure 1, is fastened to one side of the front face of the frame A of the typewriter by means of a screw 2 and to the other side by means of one or more screws 3. On the base plate are provided the guide lugs or pins 4, 4 which are spaced vertically to support and guide the horizontal cam slides 5, 6, 7, 8, 9, 10, 11, 12, 13 and 14. In addition to the vertically spaced guide lugs or pins 4, 4, horizontally spaced guide lugs or pins 15, 15 are provided on the base plate 1 to guide the

vertical cam slides 16, 16 which operate the horizontal cam slides and carry at the top the keys 17. Each of the vertical cam slides has a slightly yielding spring connecting member 18 pivotally fastened to the bottom thereof and each of these connecting members has a dog 19 formed thereon which is adapted to engage with the key levers C as will hereinafter be described. The dogs 19 are movably attached to the shift bar 20 and for this purpose are provided with a slot 21 into which engages the pin 22 carried by the shift bar 20. The shift bar is mounted to slide on the vertical base plate 1 and is supported thereon by means of the pins 23 and 24 which engage into suitable slots 25 and 26 in the shift bar so as to support the shift bar on the base plate 1 and guide it in a straight line horizontal movement thereon. The shift bar may be moved manually in either direction by means of the bell crank lever 27 which is pivotally mounted on the base plate 1 at 28 and is provided with a key 29 on the free end thereof. The connection between the bell crank and the shift bar is provided by a pin 30 which is carried on the shift bar 20 and engages into the slot 31 provided in the bell crank lever 27.

In depressing the key 29, the bell crank lever is rocked and moves the shift bar 20 to the left in Figure 1 carrying with it the pins 22 which swing the spring connecting members 18 on the lower end of the vertical cam slides 16 and move the dogs 19 thereof behind the vertical portion of the key levers C.

The vertical portion of each of the key levers C is provided at the rear, with a lug 32 so that when a numeral key E is depressed after the dogs 19 have been moved behind the key levers, as above described, the lug of its key lever engages a dog 19 and moves its connecting member 18 and the vertical cam slide 16, to which the connecting member is attached, during part of the movement of the key lever which is being depressed by the numeral key. In this way each of the numeral keys E of the typewriter, when depressed, operates a corresponding vertical cam slide 16 on the calculating attachment when the shift bar 20 has been operated by the key 29 to provide the connection between them, as above described, and moves this vertical cam slide downwardly in a vertical movement.

When it is desired to operate the calculating mechanism without operating the numeral keys of the typewriter in order to make a calculation without recording it, key 29 is raised to move the shift bar to the right and swings the dogs 19 to the right of the key levers so that they no longer are engaged by the lugs 32 thereof. The calculating mechanism, instead of being operated by the numeral keys of the typewriter, is then operated by means of the keys 17 which are carried by the vertical slide bars at the top thereof.

Each of the vertical cam slides 16 is provided with a pair of cam lugs 33 and 34 of which cam lug 33 engages one of the horizontal cam slides 5 to 13 inclusive, while cam lug 34 passes thru the cam slots 35 provided in the horizontal cam slide 14. In addition to the cam lugs 33 and 34, each of the vertical cam slides is also provided with a stop lug 36. The horizontal cam slides 5 to 13 inclusive are each provided with a lug 37 which is located on the right hand side of the vertical cam slides and cooperates with the cam lugs 33 thereof so that when these cam slides are moved downwardly, each vertical cam

slide moves a particular horizontal cam slide to the right.

While each cam lug 33 thus moves one of the horizontal cam slides 5 to 13 inclusive to the right, the cam lug 34 operates the horizontal cam slide 14 and moves it to the left on the downward movement of any one of the vertical cam slides 16. After one of the vertical cam slides 16 has been depressed by either its own key 18 or the numeral key E connected thereto, it is returned to its normal position by a spring 38 which has its center portion wound around a supporting pin 40 so that the free ends thereof can engage under the pins or lugs 39 of two successive cam slides and hold these cam slides in their elevated starting position or move them back into this position after they have been depressed as above pointed out. Stop pins or lugs 41, provided on the base plate, engage behind the cam lugs 34 and line up the vertical cam slides in a uniform starting position. The stop lug 36 of each of the vertical cam slides is suitably spaced from the cam lug 34 and engages the stop pin or lug 41 on the downward movement of the vertical cam slides in order to limit their movements to the movement necessary for the operation of the horizontal cam slides by the cam lugs 33 and 34.

Each of the horizontal cam slides 5 to 13 inclusive carries at its outer left hand end a cam 42 as illustrated in Figure 6. These cams operate to rock the rocking levers 43 which depress the index pins 44 for the setting of the digit rack bars 45 as will hereinafter be described. The horizontal cam slides 5 to 13 inclusive each carry a suitable lug 37 which is yieldingly held in its normal inoperative position against the side of the vertical cam slide just below the cam lugs 33 thereof. Springs 47 and 48 are mounted on the base plate 1 and their ends engage either a lug 49 on the horizontal cam slides or the free ends of one of these bars in order to yieldingly force the horizontal cam slides to the left in Figure 1 while their lugs 37 engage the side of the vertical cam bars below the cam lugs 33. When one of the vertical cam slides is therefore depressed either by means of its own key 17 or a numeral key E of the typewriter, the cam lug 33 thereof forces the lug 37 to the right in Figure 1 and shifts its corresponding horizontal cam slide against the pressure of one of the springs 47 or 48. In so doing the cam 42 at the end of the horizontal cam slide moves under the end of the rocking lever 43 and rocks this lever on its fixed vertical pivot pin 43A so that its opposite end engages one of the index pins 44 and forces it into the carriage 50 on one side thereof. The opposite end of the pin thus operated by the rocking lever is forced away from the other side of the carriage and projects into the path of one of the digit rack bars 45 as will hereinafter be described.

In this way each of the nine keys 17 of the calculating attachment and the nine of the numeral keys E of the typewriter on which the calculating attachment is mounted, operate one of the index pins 44 on the operation thereof.

The index pins 44 are mounted in a sliding carriage 50 which comprises a pair of vertical plate members suitably spaced apart, one of which is provided at the top with a projection 51 which is guided by a suitable guide member 52 located above the carriage 50 as illustrated in Figures 1 and 3. This same vertical plate member of the carriage 50 is provided near the bottom with lugs 53 and 54 thru which passes the guide bar 55. In this way the carriage 50 with 75

its index pins 44 is supported to slide back and forth in the guide member 52 at the top and on the guide bar 55 at the bottom.

Movement is imparted to the carriage 50 by means of the spring 56. This spring is anchored with one end to the bracket 57 and with its other end to the lever arm 58 which is keyed to the rock shaft 59. The upper end of the lever arm is connected to the outer end of the index pin carriage 10 by means of the link 60. In order to provide a step by step movement for the carriage and allow the carriage to move only when one of the keys is operated, an escapement is provided which is operated on the operation of each of the keys. This escapement is operated by the horizontal cam slide 14 and each of the vertical cam slides pass thru a cam slot 35 as heretofore pointed out so that on the downward movement of each of the vertical cam slides the horizontal cam slide 14 is moved to the left in Figure 1. The horizontal cam slide carries a cam 61 which, when shifted to the left in Figure 1, depresses the arm 62 and rocks the shaft 63. This in turn swings the arm 64 carried on the shaft 63 so that the dog 65 thereof engages into one of the slots 66 provided in the escapement bar 67 while the dog 68 moves out of this same slot and permits the carriage to be drawn to the left by the spring 56 until the end of the slot into which the dog 30 has been engaged has reached the dog 65. When the key which has been depressed is released, the horizontal cam slide moves back so that the cam 61 allows the arm 62 to rock upwardly and raise the arm 64 so that the dog 65 disengages itself from the slot in the escapement bar 67 while the dog 68 engages into the succeeding slot 66 and allows the carriage to be drawn another short distance until the end of the next slot reaches the dog 68 and is arrested thereby. Every time one 40 of the keys is depressed, the carriage is thus allowed to move a distance equal to the distance between two consecutive index pins 44 so that the operation of the next key will engage an index pin located in the succeeding vertical line of index pins in the carriage 50.

The index pins have part of their intermediate body portion reduced in diameter and a series of bow springs 70 are placed between the upright plate members of the carriage 50 and encircle in a serpentine path the reduced sections of the horizontal lines of consecutive index pins in order to make frictional contact therewith to frictionally hold the index pins in the position into which they have been moved by the rocking levers 43. These springs also serve as keys which lock the index pins into the carriage and prevent them from entirely moving out therefrom in either direction.

While the index pins have been set up by the keys, the carriage has been moved so that the operated index pins will form stops for the digit rack bars 45 on the downward movements thereof. Each digit rack bar is adapted to rotate a counter wheel 45A with which it is brought into mesh on its return movement from contact with one of the set up index pins. The digit rack bars 45 are moved to engage the index pins by the operation of the operating lever 72 which is keyed to the shaft 73. This shaft carries the arm 74 at the back of the base plate 1 as illustrated in Figure 4 which is connected by a link 75 to the vertical slide carriage 76. The carriage carries two racks 77 and 78 at the back thereof which mesh with the pinions 79 and 80 respectively and rotate these pinions and with them the shaft

81 on which they are keyed for a purpose that will presently appear.

The carriage 76 is provided with suitable side members 82 and 83 (see Figures 3 and 6) and in each of these side members is provided an elongated slot 84 between which the supporting bar 85 is suspended by means of two suspension springs 86 and 87. The bar 85 supports the lower bifurcated ends of the slides 89 which carry at their tops, lugs 90 between which and the fixed lugs 91 are stretched the springs 92 as shown in Figure 3, one for each of the nine slides 89. These springs hold the slides 89 yieldingly against the supporting bar 85 and move with this bar when it is moved by the operation of the operating lever 72. Each of the digit rack bars 45 is mounted on one side of one of the slides 89 as illustrated in Figures 3 and 8. For this purpose each digit rack bar 45 is provided with a pair of rearwardly extending extensions 93 and 94 which are provided with the slots 95 and 96 respectively and into these slots engage the pins 97 and 98 respectively to guide and hold the digit bars or racks 45 in a short straight line movement on the slides 89. A spring 99 is stretched between the lug 100 provided on the rearward extension 94 of each digit bar or rack 45 and a pin 101 carried by the slide 89 on which this digit bar or rack is mounted. In this way each digit bar or rack 45 has a predetermined lost motion on its slide 89.

When the carriage 76 is pulled down on the operation of the lever 72 it does not disturb the position of the supporting shaft 85 until the carriage has been moved a distance equal to the length of the slots 84 provided in the sides thereof. This lost motion of the carriage is transmitted to the shaft 81 to operate means for rocking the counter wheels in and out of mesh with the digit bars or racks and also for operating locking means which prevent the operating lever 72 from returning to its normal starting position unless the lever has first been given its full predetermined movement. The latter locking means comprises a mutilated ratchet wheel 102 which is keyed to the end of the shaft 81 and cooperates with a spring operated pawl 103 which is pivotally mounted below this ratchet wheel and is held by the spring 104 to normally project into the mutilated or cut out portion of the ratchet wheel. When therefore the shaft is rotated by the movement of the carriage 76 on the downward movement of the handle 72, the pawl is swung to one side and consecutively engages between the ratchet teeth of the ratchet wheel to keep it from turning back until a complete revolution of the ratchet wheel has been made and the pawl again projects into the cut away periphery thereof. When the handle 72 is released the spring 72A (see Figure 1) draws it back to its starting position and during this later movement the shaft is rotated in the opposite direction so that the ratchet wheel swings the pawl to the opposite side to consecutively engage between the ratchet teeth to keep it from turning back until the ratchet wheel has made a complete revolution in the opposite direction and the pawl again projects into the cut away portion thereof.

In its movement to operate the calculating mechanism after it has been set up by the keys thereof or the keys of the typewriter, the operating lever 72 also throws out the connection between the keys E of the typewriter and the vertical cam slides 16. This is accomplished thru the extension arm 105 which is attached to the end of the shift bar 20. This extension arm has 75

a shoulder 106 provided on the upper edge thereof and when the shift bar is shifted to the left in figure 1 on the operation of the key 29 to bring about the connection between the vertical slide bars and the typewriter keys E, the shoulder 106 is moved to the left and located below the cam 107 while the end of the arm passes thru a suitable opening in the side wall of the casing (see Figures 1 and 2). This cam has two cam lugs 108 and 109. Of these, cam lug 108 normally engages the outer end of the extension arm 105 and holds the shoulder 106 thereof away from the cam lug 109 when the handle 72 is in its normal inoperative position. As soon as the handle is depressed the cam lug 108 moves away from the end of the extension arm and permits it to swing up so that the shoulder 106 thereof will engage behind the cam lug 109 after the handle 72 has been completely operated. If the shift bar 20 has been moved to connect the typewriter keys E with the calculating mechanism, the shoulder 106 of its extension arm is located approximately below the vertical center line of the cam 107 so that on the return of the handle 72 by the spring 72A, the cam lug 109 engages the shoulder 106 and forces the extension arm back to the right in Figure 1 and shifts the dogs 19 to one side of the key levers to keep their keys from operating the calculating mechanism until the connection has again been made by shifting the shift bar to the left on the depression of the key 29.

For the purpose of keeping the operating lever from returning the shift lever and breaking the connection between the typewriter keys and the calculating mechanism, a cam 110 is mounted on the inside of the casing surrounding the calculating mechanism. This cam may be manually operated to rest on the top of the end of the extension 105 of the shift bar 20 and hold this extension so that lug 109 of cam 107 cannot engage the shoulder 106 and move the shift bar back.

To automatically return the carriage 50 with its index pins to its starting position in order to clear the mechanism on the return movement of the operating lever 72, the shaft 59, on which the lever arm 58 is mounted, has the segmental gear 110 keyed thereto at the back of the base plate 1 as illustrated in Figure 4. This segmental gear meshes with the segmental gear 111 carried on the shaft 112 and segmental gear 110 rotates the segmental gear 111 on the movement of the lever arm 58 as it shifts the index pin carriage 50. On the periphery of the segmental gear 111 is provided a lug which cooperates with the latch dog 114 carried by the carriage 76 and depending therefrom as illustrated in Figure 4. The latch dog 114 is provided with a slot 115 thru which passes the pivot pin 116 mounted on the carriage 76 to support the latch dog thereon. As the carriage is pulled down by the operation of the lever 72, the pivot pin moves down in the slot 115 until it reaches the end of the slot. A further downward movement of the carriage to the end of its downward movement by the lever 72 moves the latch dog with it to have its hook shaped member 117 engage under the cam lug 113 so that when the latch dog 114 is raised on the return movement of the carriage 76, the engagement of the dog 117 with the lug 114 of the segmental gear 111 will rotate the gear and turn this gear and the segmental gear 110 with its shaft 59 and the lever arm 58 back to its starting position. The return of the lever arm in this manner moves the index pin carriage 50 back

to its starting position and any index pin which has been set by the keys and projects from back of the carriage 50 is forced back into the carriage to again project from the front of it as the pin slides past the angular cam surface 118 of the fixed cam member 119.

For the purpose of locking the latch dog 114 out of engagement with the cam lug 113 of the segmental gear 111 when it is desired to perform a multiplication by a repeated addition of the same set up, the slide 120, with its outwardly projecting flange 121, is moved to the left in Figure 4 to engage and hold the lower end of the latch dog away from the cam lug 113. The latch dog is then raised on the return movement of the carriage 76 without returning the index pin carriage 50 to its normal starting position and a repeated operation of the operating lever 72 will cause a repeated addition of the original set up of the index pins.

The latch dog is locked out by means of the repeat lever 122 which is pivoted at 123 and with one end projects into a suitable opening in the slide 120 while the other end projects to the front of the attachment and has the handle 124 formed thereon with which it can be shifted to move the slide either into or out of engagement with the latch dog. In order to hold the repeat lever in the repeat or normal position, the front of the casing thru which the lever projects is provided with the offset notches 125 and 126 at the ends of the slot 125A in which the lever moves back and forth. The end of the lever 122 then engages into one of these notches at the end of each movement to one side or the other.

The digit bars or racks 45 are adapted to operate the counter wheels only on their return movement after they have been moved down against one of the index pins. For this reason the counter wheels are mounted to rotate on the counter shaft 127 which is suspended by a pair of arms 128 and 129 from the pivot shaft 130. The end of the counter shaft 127 is connected with the carriage 76 by a combination of toggle and rocking levers 131, 132 and 133 which are so arranged that during the first part of the movement of the carriage before the supporting shaft 85 is moved by it to allow the digit bars to move, the toggle lever 133, in moving down with the carriage, rocks the rocking lever 132 which in turn forces the toggle lever 131 to the right in Figure 2 and swings the counter shaft 127 with its counters out of mesh with the digit or rack bars 45. The digit bars are then free to move down on the downward movement of the carriage 76 until their movement is arrested by an engagement with one of the index pins 44.

The carriage 76 is ready to return when all of the digit bars have been moved to their lowermost position as governed by the set up of the index pins. In this lowermost position and during the first part of the upward movement, the spring 135, which connects the two toggle levers 131 and 133, draws the counter shaft to the left in Figure 2 in order to bring the digit rack bars in mesh with the pinions 136 of the counter wheels 45. The return movement of the digit rack bars then rotates the counter wheels in accordance to their movement as governed by the set up of the index pins.

For the purpose of clearing the mechanism that is moving the counterwheels to their starting position after the sum total has been registered by them, the clearing bar 137 is slightly shifted to the right in Figure 1. This clearing bar is an

extension of the index pin carriage 50 and in the rear thereof facing the digit or rack bars 45 are provided a series of notches 138. A suitable opening in the side wall of the housing permits its end to pass thru the side wall on its movement to the left. The notches in the clearing bar are so arranged that on the starting position of the index pin carriage 50, they are held out of line with the digit or rack bars 45 and thus prevent these bars from moving downwardly. In order to allow these bars to be moved for the purpose of turning the counter wheels back to their normal starting position, the clearing bar is slightly moved to the right in Figure 1 by means of the cam 139 provided on the extension 140 of the toggle lever 131. This extension 140 projects to the front of the calculating attachment and has the key 141 provided thereon. When therefore this key is depressed to rock the toggle link 131, the cam 139 engages the end of the clearing bar and shifts it slightly to the right in Figure 1 until the notches 138 in the clearing bar are in line with the digit or rack bars 45 and permit these bars to be operated without being arrested in their movement by the index pins on the movement of the operating lever 12. The return movement of the digit or rack bars, after being uniformly operated, then resets the counter wheels to their zero position, by means described below.

The counter wheels are stopped in their zero position by the dogs 145 which are carried by the rock shaft 146. This rock shaft is rocked by the engagement of the dog 147 provided on the extension 140 of the toggle lever 131 with the dog 145A so that on the depression of the key 141 the projections provided by the dogs 145 are then rocked against the periphery of the counter wheels and stop the wheels when their lugs 148 provided on the periphery of the counter wheels make contact therewith.

When a counter wheel is rotated more than one revolution the amount of one revolution of this counter wheel is carried over to the digit bar of the next succeeding counter wheel. This is done by the swinging latches 149 which are mounted to swing on the pivot shaft 130. Such a latch is provided for all but the last of the counter wheels. The lower ends of the swinging latches normally rest against the periphery of the counter wheels and when one of them is rotated more than one revolution, the lug 148 provided on the periphery of the counter wheel, rocks the latch and forces the upper end of the latch away from the upper ends of the digit or rack bar of the next succeeding counter wheel in order to allow the digit or rack bar to move up higher during its return movement and rotate the counter wheel an extra tenth of a revolution to carry over and add to this counter wheel the amount of a complete revolution of the previous counter wheel.

The upper end of the latches 149 are locked away from the top of the digit bars by means of the spring latches 150 which engage into the notch 151 when the latches are rocked as above described.

After the next set up of an amount and the operation of the operating lever to move the carriage 76 down previous to the movement of the counter wheels by the digit or rack bars, the latches 149 are swung back to their normal position by the horizontal resetting bar 152. This resetting bar is located in front of the upper portion of the latches 149 and is supported and

mounted to swing on the pivot shaft 130 by means of the arms 153 and 154. A link 155 is attached to the inside of the resetting bar and connects this bar to one end of the bell crank 156. A slotted link 157 (see Figure 4) is pivoted to the other end of the bell crank 156 and into the slot of this link projects the stud 158 carried by the carriage 76. The length of the slot in the link 157 is such that on the last portion of the downward movement of the carriage 76 by the operating lever 12, the stud 158 draws the link 157 with it and rocks the bell crank 156 which in turn draws the link 155 to the left in figure 2 and rocks the resetting bar toward the digit bars so that the upper portion of any of the latches 149 which have been previously swung away from the digit bars are forced back to have the hook 160 overhang the top of the digit bar and provide a stop for it. In the latter position the spring latch 150 engages the notch 151 to hold the latch yielding locked in this position while the resetting bar 152 is swung back to its starting position.

The index pin carriage 50 has a handle 142 projecting to the front of the calculating attachment. This handle is provided with a pointer 143 which projects upwardly from the handle and indicates the position of the carriage during its operation on the column indicator 144. The handle 142 is provided for the purpose of "Erasing" any amount set up by the keys before the operating handle is operated. This is done by simply shifting the carriage 50 back to its starting position by pushing the handle 142 to the right in Figure 1.

For the purpose of locking the counter wheels in engaged or in disengaged position relative to the digit or rack bars, the end of the counter shaft 127 carries the locking arm 162. This arm projects thru the vertical base plate 1 and its free end is suspended by means of the spring 163 to have the lug 164 thereof engage into either the notch 165 or 166 provided in the fixed latch plate 167. The free end of the locking arm overhangs the locking cam 168 carried on the shaft 81. This cam is so positioned on the shaft that the cut away portion of it is normally located at the top at the beginning of the movement of the carriage 76. The locking arm 162 is thus free to be drawn to the right in Figure 3 on the swinging of the counter shaft to move the counter wheels out of mesh with the digit rack bars on the first part of the rotation of the shaft 81 and moves the lug 164 of the locking arm into engagement with the notch 165 in the latch plate 167. The locking cam then engages the under side of the locking arm and holds the lug 164 locked in place in the notch 165 of the latch plate until the shaft 81 and cam 168 has made a complete revolution during the downward movement of the carriage 76. A detent 200 supported on the casing and projecting in close proximity to the periphery of each of the numeral wheels so as to engage the lugs 148 thereof, serve to align the numeral wheels and prevent their rotation when disengaged from the racks. At the end of the revolution of the shaft and cam, the cut away portion is again located under the end of the locking arm and this permits the countershaft to be moved to the left to bring the counter wheels in mesh with the digit rack bars for the operation of the counter wheels by the digit rack bars on their upward return movement. The counter shaft 127 when it is swung back moves the locking arm to the left in Figure 5 to have the lug 164 thereof move out of the notch 165 into the notch 166 75

of the latch plate 167. The rotation of the shaft 81 and the cam 168 on the upward return movement of the carriage 76, then locks the locking arm against the latch plate to hold the counter 5 wheels locked in mesh with the digit rack bars.

From the foregoing it will be apparent that I have devised a new and useful calculating attachment for typewriters which embodies the features enumerated in the statement of the invention and the above description and, while I have in the present instance shown and described preferred embodiments thereof which will give in practice satisfactory and reliable results, it is to be understood that these embodiments are 10 susceptible of modification in various particulars without departing from the spirit or the scope of the invention or sacrificing any of its advantages.

The attachment does not impair in any way the operation of the typewriter as such and the 15 recording of the amounts set up on the calculating attachment may be done at any point on the typewriter platen F.

I claim:

1. A combined typewriting and calculating machine having a carriage, a platen carried by said carriage and a type operating mechanism cooperating with said carriage, a calculating mechanism, keys for operating said type operating mechanism and carriage, keys for setting up said calculating mechanism and connecting means for connecting said type operating keys with said calculating mechanism set up keys, to simultaneously operate both said type operating mechanism and said calculating mechanism on the 25 operation of said type operating keys, an operating lever for registering each set up on said calculating mechanism and means operated by said operating lever to disengage said connecting means between said type operating keys and calculating mechanism set up keys.

2. In a calculating attachment for typewriters having numeral keys, the combination of a keyboard having substantially vertical key stems, a registering mechanism, connecting members carried by said key stems, shifting means for moving said connecting members into engagement with said numeral keys, an operating lever for causing the operation of said registering mechanism, and means moved by said operating lever 45 to operate said shifting means so as to disconnect said connecting members from said numeral keys.

3. In a calculating attachment for typewriters having numeral keys, the combination of a keyboard having substantially vertical key stems forming cam slides, a registering mechanism, connecting members carried by said cam slides, shifting means for moving said connecting members into engagement with said numeral keys, an 55 operating lever for causing the operation of said registering mechanism, an extension arm pivoted on one end of said shifting means, cam means carried by said operating lever and adapted to engage and move said extension arm in one direction on the operation of said operating lever so as to operate said shifting means to disconnect said connecting means from said numeral keys.

4. A combined typewriting and calculating machine having a movable carriage, a platen carried by said carriage and a stationary type operating mechanism cooperating with said carriage, a calculating mechanism, keys for operating said type operating mechanism and carriage,

keys for indexing said calculating mechanism, connecting means for engaging said type operating keys with said calculating mechanism operating keys to jointly operate said calculating operating keys with said type operating keys on 5 the operation of said type operating keys, an operating lever for said calculating mechanism, and disconnecting means operated by said operating lever of said calculating mechanism for disconnecting said type operating keys from said 10 calculating mechanism operating keys on the operation of said calculating mechanism by said operating lever.

5. A combined typewriting and calculating machine having a movable carriage, a platen carried 15 by said carriage and a type operating mechanism cooperating with said carriage, a key board for operating said type operating mechanism and carriage, a second key board for indexing said calculating mechanism, means for supporting said 20 calculating mechanism key board in a predetermined position with relation to said typewriter key board and for supporting said calculating mechanism to one side of said key board and detachable connecting means connecting the keys 25 of said type operating key board with the keys of said calculating mechanism key board, an operating lever for said calculating mechanism and means operated by said operating lever of said calculating mechanism for operating said 30 detachable connecting means to disconnect said type operating key board from said calculating mechanism key board.

6. The combination with a typewriter having a series of numeral keys, of a calculating machine 35 attachment having a keyboard, connecting means connecting said numeral keys of said typewriter with said calculating machine keyboard to enable an operation of said calculating machine key board by said numeral keys, a calculating mechanism, and an operating lever for said calculating mechanism, said connecting means between 40 said numeral keys and said calculating machine keyboard being disconnected by the operation of said lever.

7. In a calculating attachment for attachment to typewriters having numeral keys with a registering mechanism embodied in the calculating attachment the combination of a supporting member mounted on the front of the typewriter, 50 a keyboard carried by said supporting member, connecting means connecting said keyboard with said numeral keys and means for operating said connecting means to disengage said connecting means from said numeral keys on the operation 55 of said registering mechanism.

8. In a combined calculating and typewriting machine including a registering mechanism the combination of a keyboard for said typewriting machine, a keyboard for setting up said registering mechanism, said second keyboard being vertically in line with the numeral keys of said typewriting machine keyboard, a shifting bar extending from one side of said keyboard to the other side thereof, keyboard connecting means carried by said shift bar, a lever at one end of said shift bar for moving said shift bar to have said connecting means connect the keyboard of said typewriting machine with the keyboard of said calculating machine, and an operating lever for 60 operating said shift bar and causing said connecting means to disconnect said keyboards.

CHARLES H. SAMPSON.
